UNITED STATES PATENT OFFICE.

EUGENE JEANJAQUET, OF SWARTZ CREEK, MICHIGAN.

VAGINAL SYRINGE.

1,382,982.

Specification of Letters Patent. Patented June 28, 1921.

Application filed June 28, 1920. Serial No. 392,278.

To all whom it may concern:

Be it known that I, EUGENE JEANJAQUET, a citizen of the United States of America, residing at Swartz Creek, in the county of Genesee and State of Michigan, have invented certain new and useful Improvements 5 in Vaginal Syringes, of which the following is a specification, reference being had therein to the accompanying drawings.

- 10 This invention relates to that class of vaginal syringes in which means are provided for dilating the vagina and for educting the injected liquid, and has for its object an improvement in the structure shown in 15 Letters Patent No. 458,022, dated August 18, 1891, whereby the parts of the device may be more readily separated for cleaning and sterilizing.

In the drawings:

- 20 Figure 1 is an elevation of my improved syringe with the dilating fingers shown partly opened, all the parts being in operative position;

Fig. 2 is a central longitudinal section 25 showing the bulb E' detached and the terminals of the braces removed from the collar O;

Fig. 3 is a cross section on the line 3—3 of Fig. 2;

30 Fig. 4 is an end view of the collar O taken in the direction indicated by the arrows 4—4 in Fig. 2; and

Fig. 5 is a cross section through the bushing M in the direction indicated by the 35 arrows 5—5 in Fig. 2.

A is a cylindrical eduction tube open at the front end and closed at the rear end by a head A' having a central aperture on one side of which is an inwardly extending pro-

40 jection J.

B is an outlet at the lower part of the rear end of the tube A, having a nipple C formed about the outlet for connection with a drainage tube D.

45 The induction tube E which extends through the tube A is provided at its forward end with a detachable spray head E' provided with perforations F, and at its rear end is screw-threaded at G for engagement 50 with an operating nut H having an annular flange H'.

At the rear end of the head A' is a keeper

I having a lip I' arranged to engage the flange H' to permit rotation while preventing longitudinal movement. The projection 55 J engages with a flattened portion E² of the tube E to prevent its rotation while permitting longitudinal movement.

The dilating fingers K are pivotally mounted in a bushing M secured in the front 60 end of the tube A, by means of a wire loop L passing through perforations near the ends of the fingers.

A collar O secured upon the tube E near its front end has formed therein an annular 65 groove O' having notches O² to receive the terminal members P' of braces P which are pivotally connected at their other ends with the fingers K by means of pins Q' extending across the channels or grooves Q formed in 70 the inner faces of the fingers K.

The detachable spray head E' is screw-threaded to engage the threaded end T of the tube E, and is provided with an end flange R which engages the front end of the 75 collar O to hold the terminal members P' in the notches O² and groove O'.

A flexible tube S is attached to the end G' of the induction tube E to furnish a supply 80 of liquid.

The operation of the parts will be obvious 85 from the description, the structure differing from that of the former patent cited only in the improved means employed to render the braces P readily separable from the tube E, so that by unscrewing the spray head E', the terminals P' may be lifted out of the notches O² and the tube E be withdrawn through the front end of the tube A after unscrewing the nut H from the threaded 90 portion G.

I claim:

In a vaginal syringe, an eduction tube having an induction tube movable axially thereof, a series of dilating fingers, each finger being pivotally mounted at its rear end to the eduction tube, and a series of braces, each being pivotally secured at one end to one of the dilating fingers, and at the opposite end being provided with a terminal member, a collar upon the induction tube having formed therein on its forward face an annular groove and having notches to receive the terminal members of the braces,

and a spray head secured detachably upon the front end of the induction tube and arranged so that when in operative position, its rear portion forms a closure for the annular groove in the collar, to hold the terminal members of the braces in pivotal engagement therewith.

In testimony whereof I affix my signature in presence of two witnesses.

EUGENE JEANJAQUET.
